TIME DELAY RELAY

Carl H. Larson, Elkhart, Ind., assignor to The Adlake Company, a corporation of Illinois

Application May 3, 1939, Serial No. 271,549

4 Claims. (Cl. 260—97)

This invention relates to mercury switch relays, and in order to understand the objects of the invention, it is necessary to define certain terms that will be used:

5 *Normal operate time* is the time required to produce a change in the electrical circuit through the switch when the relay winding is suddenly closed while all parts of the switch are lying in stable equilibrium.

10 *Normal release time* is the time required to produce a change in the electrical circuit through the switch when the relay winding is suddenly opened while all parts of the switch are lying in stable equilibrium.

15 *Normal operate recycling time* is the minimum period during which the relay winding must be permitted to remain open in order that the normal operate time is obtainable when the relay winding is suddenly closed. Usually, though not always, the normal operate recycling time is the same as the time required for the switch elements to reach stable equilibrium after the relay winding has been opened.

20 *Normal release recycling time* is the minimum period during which the relay winding must be permitted to remain closed in order that the normal release time is obtainable when the relay winding is suddenly opened. Usually, though not always, the normal release recycling time is the same as the time required for the switch elements to reach stable equilibrium after the relay winding has been closed.

25 *Quick operate reset* refers to the ability of a switch to give normal operate time without requiring a particular time interval to precede the closing of the relay winding.

30 *Quick release reset* refers to the ability of a switch to give normal release time without requiring a particular time interval to precede the opening of the relay winding.

35 Obviously in writing commercial specifications for relays of this kind, minimum and maximum values are often given for operate and release time, these values representing time intervals which must be met regardless of the relative positioning of the switch parts (i. e. in stable equilibrium or not) at the instant that the condition of the electrical circuit through the relay winding is changed. The minimum values are usually specified to prevent an immediate change in circuit condition in the event of sub-normal recycling conditions, and the maximum values are usually given to hold the operation of the relay to reasonable cycles or to meet some other special operating condition.

40 With the above definitions in mind, the principal object of the invention is to provide a mercury switch relay of the slow make, slow break type characterized by its ability to meet specifications for minimum release time in the event of

sub-normal release recycling time, and characterized further by the fact that the relay switch has quick release reset properties.

45 A further object is to accomplish the above result by the use of two cooperating and interdependent time delay elements.

50 Further and other objects and advantages will become apparent as the disclosure proceeds and the description is read in conjunction with the accompanying drawing, in which

55 Fig. 1 is a vertical sectional view of a relay embodying the principles of this invention, the switch parts being shown in the position which they assume immediately after the relay coil has been de-energized; and

60 Fig. 2 is a view similar to Fig. 1 but showing the switch parts in the position which they assume immediately after the relay coil has been de-energized for a period corresponding to normal operate recycling time and then suddenly energized.

65 A preferred form of the invention has been illustrated in the drawing and will be hereinafter described in compliance with Sec. 4888 of the Revised Statutes, but the invention is not limited to the specific disclosure contained herein and the appended claims should be construed as broadly as the prior art will permit.

70 There are some electrical circuits in which a relay used to control the operation of other electrical equipment, must be incapable of closing the contacts of the relay switch until after a given time interval has elapsed following the de-energization of the relay coil. The relay of this invention may be used satisfactorily to fulfil such conditions.

75 It is unnecessary for the purpose of this disclosure to show any of the numerous circuits which may require a relay of this kind, and it will be sufficient to describe the relay in terms of its operating characteristics.

80 The relay comprises a coil 10, connected to a source of E. M. F. 11 and controlled in its operation by suitable circuit interrupting means, which may here be diagrammatically indicated as a switch 12.

85 A mercury switch 13 of the mercury displacement type is mounted in operative relation to the coil 10 and comprises a switch envelope 14 of low expansion boro-silicate glass through the base of which lead-in wires 15 and 16 of molybdenum, tungsten, or the like are pinch-sealed. A glass sleeve 17 surrounds the lead-in 16 to a point adjacent its upper end, leaving an exposed electrode portion 18 projecting above the sleeve 17. A ceramic cup 19 is bonded, preferably by fusion, to the sleeve 17 to retain a pool of mercury in contact with the electrode 18.

90 A glass thimble, generally designated 20 is telescoped over the upper portion of the lead-in 16

and is fused to the sleeve 17 and upper end of the lead-in 18, as indicated at 21. The bond between the thimble 28 and the sleeve 17 is spaced from the bottom of the switch envelope 14 in order to leave an electrode portion 22 of the lead-in 18 exposed to the mercury fill 23 in the envelope.

The thimble 28 is closed at the top by a porous wall 24 of ceramic material, such as Alundum, grade RA98, manufactured by the Norton Company of Worcester, Massachusetts. The ceramic material has the property of permitting gas to pass through it at a predetermined rate for the purpose of controlling certain time delay characteristics of the switch and yet the material is impervious to mercury.

A relatively large opening 25 is provided in the side wall of the thimble 28 to permit free passage of mercury from the interior of the thimble 28 to the remainder of the mercury fill, modified only by gas pressure differentials that are set up in prescribed ways to obtain the desired time delay characteristics of the switch.

A mercury displacer or plunger, generally designated 26, is telescoped over the thimble 28 and comprises an armature 27 encircling an inner glass sleeve 28 closed at its upper end by a plug 29 of ceramic material similar in its properties to the ceramic plug 24 associated with the thimble 28. The plug 29 preferably is chosen so that it will offer less impedance to the flow of gas than the plug 24, but the exact characteristics of the plug are necessarily determined by the desired operating characteristics of the switch. The sleeve 28 is provided with a bulge 30 to form a seat for the armature sleeve 27, and guide washers 31 flank the armature 27 to guide the movement of the displacer within the envelope. It should be understood that the washers 31 have numerous cut-outs in their periphery to permit mercury to pass freely from one side of the washer to the other side thereof. The upper guide washer is held in place by a cushioning spring 32 which is telescoped over the projecting end of the glass sleeve 28 and a similar cushioning spring 33 is telescoped over the lower end of the sleeve 28.

The entire switch envelope is filled with a suitable gas, such as helium, hydrogen, or a mixture of the two before being sealed off at 34.

Operation

Whenever the coil 16 is energized, the plunger 26 is pulled completely out of the mercury as shown in Fig. 2, due to the positioning of the coil, and pole sleeves 35 and 36 relative to the armature 27.

Whenever the coil 16 is de-energized, the entrapment of gas within the displacer thimble 28 always forces the mercury level within that thimble to a position that is below the uppermost portion of the opening 25 so that whatever mercury is within the glass thimble 28 immediately falls away from the electrode 18 due to the undermining of the mercury column in the thimble 28 by the gas in the displacer thimble 28. The weight of the displacer 26 is made sufficiently great so that whenever the coil 16 is de-energized, it moves at once to the position in which it is shown in Fig. 1 so that substantially instantaneously, the mercury column in the fixed thimble 28, whatever may be its height, is lowered to the level indicated by the line 37.

Let us assume that the switch parts are in the position shown in Fig. 1 and that the relay coil

16 is not energized until all parts of the switch have had an opportunity to reach stable equilibrium. Under such circumstances, it is obvious that the time required for the mercury within the displacer thimble 28 to rise within the fixed thimble 28 and make contact with the electrode 18 is determined, first, by the action of the time delay element 29 associated with the displacer (this time delay element controls exclusively the time required for the mercury level in the displacer to rise from the position indicated by the broken line 37 to the top of the opening 25); and secondly, by the combined actions of the time delay elements 24 and 26 (after the mercury level within the displacer has reached the top of the opening 25, it is the time delay element 24 modified slightly by the action of the time delay element 26 which controls the movement of mercury upwardly within the thimble 28 to the exposed end 18 of the lead-in 18). If, then, the time delay elements 24 and 26 are properly chosen, it is possible to have the combined actions of the time delay elements provide a given time interval for the making of the circuit through the lead-ins 15 and 18 after the relay coil 16 has been de-energized.

Now let us assume that the coil 16 has been de-energized a sufficient length of time so that all parts of the switch are in stable equilibrium with the final mercury level, as indicated by the position of the line 38. In other words, we are assuming that normal operate recycling time for this particular relay has elapsed. If, now, the coil 16 is energized to raise the plunger 26 to the position in which it is shown in Fig. 2, the mercury level falls to a position indicated by the line 39 which, it should be observed, is above the top of the opening 25 in the fixed thimble 28. Because of this last circumstance, the mercury within the thimble 28 is not undermined, and the time required for the column to fall from the level 38 to a point just below the top of the cup 18 (at which instant the circuit between the electrodes 18 and 22 is broken) is determined solely by the action of the time delay element 24 which slowly admits gas to the interior of the thimble in order to establish stable equilibrium. Obviously by properly establishing the desired vertical positioning of the electrode 18 within the thimble 28, the time interval for breaking the circuit (i. e. normal operate time) may be fixed at any desired value within limits. The mercury finally levels off at 48 (Fig. 2).

The fact that whenever the coil 16 is de-energized, the mercury level within the displacer is brought down to a level below the top of the opening 25 regardless of the mercury level within the thimble 28 at the instant when the coil is de-energized, is in effect saying that the switch is characterized by a quick release reset feature. But in the present case, this feature is only incidental to the real purpose of this particular arrangement. Were it not for the particular arrangement, there is one condition under which a false make of the circuit through the switch would be obtained instantaneously upon de-energization of the coil 16, a condition which would render the relay unsuitable for use in circuits requiring relays with minimum release time under conditions of sub-normal release recycling time.

For example, let it be assumed that the opening 25 in the fixed thimble 28 were located somewhat lower than shown in the drawing, so that at all times, it is below the mercury level. In such a case, it is possible to have a condition

in which the mercury level within the thimble 28 has, pursuant to energization of the coil 10, fallen to a position just below the top of the cup 18 (and consequently broken the circuit through the switch) and immediately after the circuit has been broken, the coil 10 has been suddenly de-energized. The quick drop of the plunger 26 in such circumstances would cause the mercury within the thimble 28 to surge upwardly and produce a substantially instantaneous closing of the circuit through the electrodes 18 and 22 and without the elapse of the prescribed minimum release time. It is to avoid this condition that the relay of this invention is designed to give minimum release time in spite of sub-normal release recycling time.

It is obvious from the hypothetical condition set forth above, that if the opening 25 is placed, as shown in Figs. 1 and 2, the de-energization of the coil 10 without the elapse of normal release recycling time, cannot result in causing the switch to close its contacts before the elapse of minimum release time, and in the particular embodiment of the invention disclosed, the switch contact cannot be closed at any time in less than normal release time.

It should be noted that in the particular relay shown, the specifications permit a subnormal operate time of zero, for it can readily be seen that if the coil 10 is energized immediately after the circuit between the electrodes 18 and 22 has been closed, the circuit will at once be re-opened.

By way of specific example, but by no means limiting the scope of this invention, let us suppose that the relay specifications call for 45 seconds normal operate time, two minutes normal release time, and two seconds minimum release time in case of sub-normal release recycling time, the switch of this invention would fill the specifications by selecting the plug 29 so that it would of itself produce, let us say, eight seconds of time delay (to bring about stable equilibrium assuming the fixed thimble 28 were omitted) and by choosing the plug 24 so that it would produce a 45 second time delay in permitting the mercury column to fall from the level 38 (Fig. 2) to the point where it breaks the circuit through the switch.

What I claim is:

1. In a mercury switch relay having a predetermined minimum release time, the combination of a relay coil, a switch of the slow make, slow break type associated with the coil, said switch comprising a switch envelope, spaced electrodes in the envelope, a mercury fill, a hollow displacer responsive to the coil for shifting the mercury level, a time delay element carried by the displacer and arranged so that downward movement of the displacer in the mercury fill causes the mercury to slowly rise in the displacer at a rate proportionate to the action of the time delay element, while upward movement of the displacer causes the mercury to move quickly in a direction that tends to empty the displacer of mercury, and a second time delay element comprising a thimble provided at the top with a restricted gas opening and at the side with an opening for the free passage of mercury, said two time delay elements being so correlated that for normal recycling time, the normal operate and release times are obtained, but for sub-normal release recycling

time, the predetermined minimum release time is effected.

2. In a mercury switch relay, the combination of a relay coil, a switch of the slow make type associated with the coil, said switch comprising a switch envelope, spaced electrodes in the envelope, a mercury fill, a hollow displacer responsive to the coil for shifting the mercury level, a time delay element carried by the displacer and arranged so that downward movement of the displacer in the mercury fill causes the mercury to slowly rise in the displacer at a rate proportionate to the action of the time delay element, while upward movement of the displacer causes the mercury to move quickly in a direction that tends to empty the displacer of mercury, and a second time delay element including portions rigidly telescoped over one of the electrodes and arranged with respect to the displacer and other switch elements so that downward movement of the displacer causes the switch electrodes to open at once, if not already opened, and be thereafter incapable of closing until after the lapse of a predetermined minimum period of time, regardless of subsequent movements of the displacer.

25

3. In a mercury switch relay, the combination of a relay coil, a switch of the slow make type associated with the coil, said switch comprising a switch envelope, spaced electrodes in the envelope, a mercury fill, a hollow displacer responsive to the coil for shifting the mercury level, a time delay element including portions rigidly telescoped over one of the electrodes, said displacer being substantially closed at its upper end to form a gas pocket therewithin adapted to contain a predetermined minimum volume of gas and being constructed and arranged so that the downward movement of the displacer causes the gas trapped within the displacer to force mercury downwardly to open at once, if not already open, the switch electrodes, whereafter said time delay element prevents the electrodes from being bridged with mercury until after the lapse of a pre-determined minimum period of time, said displacer on its upward stroke being raised a distance sufficient to place the interior of the displacer in gaseous communication with the exterior thereof to assure the presence of the predetermined minimum volume of gas within the gas pocket that is effective for forcing mercury downwardly to open the electrodes on the next downward stroke of the displacer.

30

4. In a mercury switch relay having prescribed operating characteristics, the combination of a relay coil, a switch associated with the coil, said switch comprising a switch envelope, spaced electrodes in the envelope, a mercury fill, a hollow displacer responsive to the coil for shifting the mercury level, and cooperating time delay elements associated with one of said electrodes to delay the movement of mercury with relation to said electrode upon a change in the condition of the electrical circuit through the coil, one of said time delay elements comprising a gas leakage device associated with the displacer and the other comprising a relatively fixed gas leakage device associated with said one electrode, and means including at least one of said time delay elements for insuring that the switch shall possess minimum release time characteristics.
